UNITED STATES PATENT OFFICE

160,813

FOUNT FOR KEROSENE OIL LAMPS

Samuel Scherr and French Eugene Smith, Akron,
Ohio, assignors to S. F. Appliances, Limited, a
corporation of New Jersey

Application September 8, 1949, Serial No. 4,911

Term of patent 3½ years

(Cl. D48—21)

To all whom it may concern:

Be it known that we, French Eugene Smith and Samuel Scherr, both citizens of the United States, residing at Akron, county of Summit, and State of Ohio, have invented a new, original, and ornamental Design for Fount for Kerosene Oil Lamps, of which the following is a specification, reference being had to the accompanying drawing, forming a part hereof.

Fig. 1 is a side elevational view of a fount for kerosene oil lamps showing our new design; and Fig. 2 is a top plan view thereof.

The dotted lines shown in the drawing are for illustrative purposes only.

We claim:

The ornamental design for a fount for kerosene oil lamps, as shown and described.

SAMUEL SCHERR.
FRENCH EUGENE SMITH.
